SURFACE GRINDERS

James Selby, Hatch End, England, assignor to B. Elliott & Company Limited, London, England, a British company
Filed June 6, 1966, Ser. No. 34,006
22 Claims. (Cl. 51—92)

This invention relates to surface grinders. The object of the invention is the provision of an improved machine for surface grinding, and the invention consists broadly of a surface grinding machine, in which a grinding wheel is adapted to grind the surface of a work-piece mounted on a work-table, which is movable in one direction relative to a saddle, which, in turn, is movable in a direction at right angles to said one direction relative to a base, wherein said machine has a control system whereby either both the saddle and the work-table are reciprocated, whereby criss-cross grinding is effected, or one of said parts (hereinafter, for convenience, assumed to be the work-table) is reciprocated, whilst the other part (hereinafter, for convenience, assumed to be the saddle) is moved step by step unidirectionally, whereby step-by-step grinding is effected.

In order that the invention may be the more clearly understood, a machine in accordance therewith will now be described, reference being made to the accompanying drawings, wherein:

FIGURE 1 is a somewhat diagrammatic front elevation of the machine.

FIGURE 1A is a fragmentary plan view of FIGURE 1.

FIGURE 2 is a somewhat diagrammatic side elevation of the machine.

FIGURE 3 is a hydraulic circuit diagram illustrating the operation of the machine.

Referring first to FIGURES 1 and 2 the spindle 1 of the grinding wheel 2 rotates in a bearing carried near the upper end of a wheel head assembly 3 which is mounted on the rear external surface of a cast box-shaped base 4 so as to be slideable up and down. Said spindle 1 extends horizontally so that the grinding wheel 2 overhangs the top surface of said box-shaped base.

On said top surface of the box-shaped base is mounted a saddle b which reciprocates in a direction parallel to the axis of the grinding wheel spindle 1, and, mounted on the top of said saddle is an elongated work-table d which reciprocates longitudinally, that is at right angles to the axis of the grinding wheel spindle. By adjusting the wheel head assembly 3, the grinding wheel 2 can be adjusted to the appropriate height for grinding the surface of a given workpiece on the work-table d, and the grinding is then effected as required by making longitudinal and transverse movements with the work-table d and saddle b respectively.

Both of these movements are effected hydraulically. The movement of the saddle b relative to the base 4 is effected by means of a hydraulic cylinder a which is fast with said saddle and whose piston a1 is connected by its piston rod to said base 4 at 5. The movement of the table d relative to the saddle b is effected by means of a hydraulic cylinder c, which, like the cylinder a, is also fast with said saddle, and whose piston c2 is connected by its piston rod to said table at points 6. The movement of the saddle b and the table d may

be controlled in either of two different ways selectively. According to one way (hereinafter called step-by-step control) the table d is repeatedly reciprocated and at each reversal, or each alternate reversal, of said table, the saddle b makes a small increment of cross traverse movement. According to the other way (hereinafter called criss-cross control) the saddle b, as well as the

2

table d, is continuously reciprocated so that criss-cross grinding is effected. Thus, when step-by-step grinding is to be carried out, liquid is injected alternately into opposite ends of the table cylinder to cause the piston c2 to reciprocate continuously through its full stroke, and a metered quantity of liquid is injected into the saddle cylinder a at each reversal of the piston c2 of the table cylinder. When criss-cross grinding is to be carried out, liquid is injected alternately into opposite ends of the saddle cylinder a to cause it to reciprocate continuously through its full stroke, the table cylinder c being controlled as before.

The control system by which the above is effected is illustrated in FIGURE 3 and will now be described.

Thus, referring to FIGURE 3, two separate sources of hydraulic supply e and f are provided for the saddle cylinder a and the table cylinder c respectively. These sources may consist, as shown, of respective gear pumps which take in from a tank g. When the system is set for criss-cross grinding, the table cylinder c is continuously reciprocated by liquid from the supply f, and the saddle cylinder a is continuously reciprocated by liquid from the supply e, and the two cylinders being driven independently and without being in any way synchronised. The hydraulic system for this form of grinding is straightforward and need only be described briefly.

Thus, for driving the table cylinder c, liquid flows from source f to a port h1 of a rotary direction-reversing valve h which is adapted to reverse its position—say by the action of adjustable dogs 12 mounted on a bar 14 secured to table d, on the work-table d—each time said table cylinder c reaches the end of its stroke. Said rotary direction-reversing valve h being at the position illustrated, the liquid will flow from said rotary direction-reversing valve through a port h2 thereof and thence to a port i1 at one end of the cylinder of a piston type direction-reversing relay valve i. Said direction-reversing relay valve i will therefore be at the end of its stroke opposite to its port i1 as illustrated. The other end of said cylinder of the direction-reversing relay valve is connected, by way of a port i2 therein to a port h3 of said rotary direction-reversing valve, and from thence through a port h4 of the latter to exhaust in the tank g, and thus the direction-reversing relay valve i was free to move to its illustrated position when the rotary direction-reversing valve h was first moved to its illustrated position.

The direction-reversing relay valve i being at its illustrated position, liquid flows from the source f to a port j1 of a rotary control valve j and from a port j2 of said rotary control valve to a port i3 of said direction-reversing relay valve i, and out from a port i4 of the latter to a port c1 at one end of the table cylinder c. The piston c2 of said table cylinder is accordingly driven towards the opposite end of said table cylinder. At the same time, liquid on the other side of said piston c2 is free to flow out of a port c3 in the opposite end of said table cylinder through a port in the cylinder of the direction-reversing relay valve i and out through a port i6 in said last-named cylinder to exhaust in the tank g.

When said piston c2 reaches the end of the table cylinder c having the port c3 therein, the rotary direction-reversing valve h is turned to its non-illustrated position. Liquid from the source f now flows through port h1 of said rotary direction-reversing valve and out from the port h3 thereof to said port i2 of said direction-reversing relay valve. At the same time the port i1 of said direction-reversing relay valve is connected, through the ports h2 and h4 of the rotary direction-reversing valve, to exhaust at the tank g. Said direction-reversing relay valve accordingly moves to its non-illustrated position.

Said direction-reversing relay valve i being at its non-

illustrated position, liquid flows from the source *f*, in through the port *j1* and out through the port *j2* of the rotary control valve *j*, to the port *i3* of the direction-reversing relay valve. This latter port *i3* is now connected to the port *i5* of said direction-reversing relay valve and therefore to the port *c3* of the table cylinder. At the same time the port *i4* of the direction-reversing relay valve is now connected to a port *i7* of said relay valve which is permanently connected to exhaust at the tank *g*, and therefore the port *c1* of the table cylinder is connected through the port *i4* and *i7* of the direction-reversing relay valve to exhaust. The piston of the table cylinder therefore returns to the end of said cylinder having the port *c1* therein.

The rotary direction-reversing valve *h* therefore returns to its illustrated position, so that the piston *c2* of the table cylinder *c* returns to the end of said table cylinder having the port *c3* therein and so on.

A relief valve *k* is provided whereby, if the delivery pressure of the source *f* exceeds a given value the liquid from said source returns direct to exhaust in the tank *g*.

An adjustable throttle valve *l* is provided between the port *i2* of the direction-reversing relay valve and the port *h3* of the rotary direction-reversing valve, whereby alternately the pressure flow, or the exhaust flow, through said last-named port *h3* is controlled, and therefore the speed of movement of said relay valve *i* is controlled.

For driving the saddle cylinder *a*, liquid flows from the source *e*, in through a port *m1* and out through a port *m2* of a rotary control valve *m*, and thence in through a port *n1* and out through a port *n2* of a rotary change-over valve *n*, which is now assumed to be at the position illustrated which is the position for criss-cross control, and thence in through a port *o1* in the wall of the cylinder of a piston-type direction-reversing valve *o*, which is adapted to reverse its position each time the saddle reaches the end of its stroke. The reversal of the valve is controlled by dogs *13* which should be visualized as being adjustable in reference to a base in the axial direction of valve *o*. If said direction-reversing valve *o* is assumed to be at the illustrated position, the liquid will flow through said port *o1* and a port *o2* to a port *a2* at one end of the saddle cylinder *a*. At the same time liquid on the other side of the piston *a1* of said saddle cylinder is free to flow out of a port *a3* in the opposite end of said saddle cylinder, in through a port *o3* in the cylinder wall of said direction-reversing valve *o*, and out through a port *a4* in said cylinder wall to exhaust in the tank *g*. The saddle cylinder *a* is accordingly driven towards the end of its stroke at which the port *a3* is adjacent to the piston *a1*.

When said cylinder reaches this end of its stroke, the direction-reversing valve *o* is moved to its non-illustrated position. Liquid from the source *e* now flows, as previously traced, in through the port *o1* of the cylinder of said longitudinal direction-reversing valve, and out through the port *o3* of said cylinder to the port *a3* of the saddle cylinder. Also the liquid in said saddle cylinder is free to flow out through the port *a2* thereof, and in through the port *o2* of the cylinder of the direction-reversing valve *o* and out through a port *o5* of said last-named cylinder to exhaust. The saddle cylinder will accordingly be driven back to the illustrated position. This will cause the direction-reversing valve *o* to be returned to its illustrated position, so that the saddle cylinder returns to the non-illustrated position and so on.

There is also a relief valve *p* whereby, if the delivery pressure of the source *e* for the saddle cylinder exceeds a given value, the liquid from said source returns direct to exhaust.

Describing now the system of control for step-by-step grinding, the control of the table cylinder is, of course, the same as in the case of criss cross grinding. For the control of the saddle cylinder, two additional valves are employed, both of the piston type, in which the valve reciprocates in a cylinder, viz. a table-responsive valve *q* and a metering valve *r*.

The cylinder of the table-responsive valve *q* has two ports *q1* and *q2* in its two ends which are respectively connected to the two ports *i1* and *i2* in the ends of the cylinder of the direction-reversing relay valve *i*, so that said table-responsive valve *q* is slave to said direction-reversing relay valve *i*. Thus said table-responsive valve *q* is at its illustrated position when the direction-reversing relay valve *i* is at its illustrated position and at its non-illustrated position when said direction-reversing relay valve is at its non-illustrated position.

The metering valve *r* consists simply of a cylinder with a loose piston *r1* therein and two ports *r2* and *r3* adjacent to its two ends on each side of said piston.

For changing from criss-cross grinding to step-by-step grinding, the aforesaid change-over valve *n* is moved from its illustrated position for criss-cross control to its position for step-by-step control. This cuts off the port *n1* from the port *n2* of said changeover valve, and thereby cuts off the previously traced path from said source *e* to the port *o1* of the direction-reversing valve *o*. Said movement of said change-over valve *n* also connects a port *n3* to a port *n4* thereof, and thereby establishes communication from the source to two ports *q3* and *q4* in the side of the cylinder of the table-responsive valve *q*.

Assuming that the direction-reversing relay valve *i* is at its illustrated position so that the piston *c2* of the table cylinder is travelling towards the end of said cylinder having the port *c3* therein, said table responsive valve *q* will also be at its illustrated position and consequently the port *q3* in its cylinder wall will be connected to a port *q5* in said cylinder wall which port *q5* is connected to the port *r2* in the cylinder wall of the metering valve *r*. Consequently the source will be connected, through said ports *q3* and *q5* of the table-responsive valve to the port *r2* of said metering valve, and the piston *r1* of said metering valve will be maintained at the end of its stroke towards the port *r3* of said metering valve. Said port *r3* of the metering valve is connected to a port *q6* of the table-responsive valve, and, the latter valve being at its illustrated position, said port *q6* is connected to a port *q7* of said table-responsive valve which port *q7* is connected to the aforesaid port *o1* of the direction-reversing valve *o*, and, assuming that this last valve is at its illustrated position, said port *o1* thereof is connected to the port *o2* thereof which is connected to the port *a2* of the saddle cylinder *a*.

The port *r3* of the metering valve is thus connected to the port *a2* of the saddle cylinder and in this way said saddle cylinder is being retained at the point of its step-by-step advance which it has already reached. The port *a3* of said saddle cylinder is connected, through the ports *o3* and *o4* of the direction-reversing valve *o*, to exhaust.

When the piston *c2* of the table cylinder reaches the end of said cylinder having the port *c3* therein, the table-responsive valve *q* will move to its non-illustrated position, and the port *q4* thereof will be connected to the port *q6* thereof and thence to the port *r3* of the metering valve. The source will therefore be connected to said port *r3* of the metering valve.

Also the ports *q5* and *q7* of the table-responsive valve will be connected together so that the port *r2* of the metering valve will be connected, through said ports *q5* and *q7* of said table-responsive valve to the port *o1* of the longitudinal direction-reversing valve, which is still at its illustrated position and thence, as previously traced, to the port *a2* of the saddle cylinder.

Thus the port *r2* of the metering valve is connected to the port *a2* of the saddle cylinder, and, as the port *r3* of said metering valve is connected to the source *e*, the piston *r1* of said metering valve will therefore make its stroke towards the port *r2* of said metering valve, and a measured quantity of liquid will be driven into the saddle cylinder *a* through the port *a2* thereof, and said saddle cylinder will make a step of movement towards the end of its stroke at which the port *a3* is adjacent the piston *a1*.

When the piston $c2$ of the table cylinder c again reaches the end of said cylinder having the port $c1$ therein, the table-responsive valve q will again move to its illustrated position, and thus the source e will be again connected to the port $r2$ of the metering valve and the port $r3$ of said metering valve will be again connected to the port $a2$ of the saddle cylinder. The piston $r1$ of said metering valve will accordingly make its stroke towards the port $r3$ thereof and a further metered quantity of the liquid will be driven into the saddle cylinder through the port $a2$ thereof, and the saddle cylinder will make a further increment of movement towards the end of its stroke at which the port $a3$ is adjacent to the piston $a1$.

It will thus be seen that this incremental movement of the saddle cylinder will continue step-by-step each time the piston $c2$ of the table cylinder c reaches an end of its stroke, until the saddle cylinder reaches the end of its stroke at which the port $a3$ is adjacent to the piston $a1$. When this happens, the direction-reversing valve o is moved to its non-illustrated position, and the saddle cylinder now makes incremental movements towards the end of its stroke at which the port $a2$ is adjacent to the piston $a1$.

Thus, when said direction-reversing valve o is at its non-illustrated position, the port $o1$ thereof is connected to the port $o3$ thereof and thence to the port $a3$ of the saddle cylinder, and port $o2$ of said direction-reversing valve is connected to the port $o5$ thereof and therefore the port $a2$ of the saddle cylinder is connected to exhaust. Therefore the action is the same as before except that the measured quantity of liquid is each time supplied to the saddle cylinder, through port $a3$ thereof, and the port $a2$ thereof is connected to exhaust. The saddle cylinder therefore now makes steps in the direction towards the end of its stroke which is illustrated.

To sum up, each time the table d is reversed, the saddle b makes a small step of movement and these steps continue in the same direction until the saddle has completed its predetermined stroke in that direction, whereupon the steps takes place in the opposite direction until the saddle stroke is completed in said opposite direction, and so on.

In order that the extent of each step of movement of the saddle may be varied, means are provided for varying the stroke of the piston $r1$ of the metering valve r . This means may consist simply of an adjustable screw threaded stop $r4$.

In the above description, the rotary control valves j and m have been assumed to occupy the illustrated position throughout. It will be readily seen that, by moving the control valve j to its non-illustrated position, at which the port $j1$ is cut off from the port $j2$ and is connected to the port $j3$, the source f is connected directly to exhaust and the table drive ceases to operate. In like manner, by moving the control valve m to its non-illustrated position at which the port $m1$ is cut off from the port $m2$ and is connected to the port $m3$, the source e is connected directly to exhaust, and the saddle drive ceases to operate.

Returning to FIGURES 1 and 2, a valve block 7 is provided, fast with the saddle b , in which all the valves illustrated in FIGURE 3 are contained. As both cylinders a and c are also fast with the saddle b , the conduits to said cylinders need not be flexible. The tank g is located in the base 4 and so also are the two gear pumps e and f , which are incorporated with an electric driving motor in a unit 8 (FIGURES 1 and 2). It will thus be seen that the conduits leading from said gear pumps e and f to the valve system, and also the exhaust conduit leading from the valve system to the tank, must be flexible but otherwise none of the conduits shown in FIGURE 3 need be flexible.

The only valves which have to be operated by hand are j , m , l and n . The control knobs for these valves, which are not shown, are, of course, mounted on the outside of the valve block 7 . The stroke of the metering

valve r is also controllable by hand and its control knob is mounted on the outside of the valve block 7 .

The reference 9 designates an electric motor which is incorporated in one structure with the wheel head assembly 3 and drives the spindle 1 of the grinding wheel through a belt or chain drive 10 .

The manual controls for adjusting the wheel head assembly 3 , and those also for adjusting the saddle b and work-table d when they are cut off from hydraulic control, are conventional and have not been illustrated or described.

The particular construction and arrangement described and arranged above may obviously be modified in many ways without departing from the scope of the invention.

I claim:

1. A surface grinding machine comprising a base, a saddle movably mounted on said base, a table movably mounted on said saddle, a first reversible hydraulic means operatively coupled to said table for reciprocating movement thereof in one direction from an extreme position, a second reversible hydraulic means operatively coupled to said saddle for reciprocating movement thereof in a direction transverse to said table, means for automatically reversing the direction of movement of the saddle at each end of its stroke, adjustable valve means for controlling the movement of said saddle with respect to said table, in one position of said valve means said saddle being movable in said transverse direction reciprocatingly concurrent with the reciprocation of said table, in another position of said valve means said saddle being movable in said transverse direction in at least one separate step when said table is at said extreme position along a displace path.

2. A grinding machine according to claim 1, wherein said adjustable valve means is a unitary control element having one position for criss-cross grinding and another position for the step-by-step grinding.

3. A grinding machine according to claim 1, wherein said table and said saddle are driven by respective reversible hydraulic motors each of which includes a cylinder and a piston.

4. A surface grinding machine comprising a base, a saddle movably mounted on said base for reciprocating movement relative thereto in one direction, a table movably mounted on said saddle for reciprocating movement relative thereto in a direction transverse to said one direction, a first reversible hydraulic motor operatively coupled to said table, a first hydraulic fluid supply circuit for said first motor, table reversing valve means connected in said first circuit for reversing the direction in which said first motor is driven when said table is at an extreme position, a second reversible hydraulic motor operatively coupled to said saddle, a second hydraulic fluid supply circuit for said second motor, saddle reversing valve means in said second circuit for automatically reversing the direction in which said second motor is driven, an increment feed valve in said first and second circuits for controlling the quantity of fluid in said second circuit when said table is at said extreme position to move said saddle in separate steps, and control means for selecting the operable periods of said increment feed valve and said saddle reversing valve means to provide movement of said table and said saddle reciprocating separately and concurrently together, respectively, for step-by-step and criss-cross grinding.

5. A grinding machine according to claim 4, wherein for criss-cross grinding the supply of fluid for said first motor is controlled by direction-reversing valve means which is responsive to the position of the said table so that said table is continuously reciprocated, and the supply of fluid for said saddle motor is controlled by said saddle-reversing valve means, which is responsive to the position of the saddle so that said saddle is continuously reciprocated.

6. A grinding machine according to claim 5, wherein said direction-reversing valve means includes a direction-reversing valve controlled according to the position of

said table, and a direction-reversing relay valve which is controlled hydraulically by said direction-reversing valve and which controls the said first motor.

7. A grinding machine according to claim 6, wherein an adjustable throttle valve controls the speed of movement of said direction-reversing relay valve.

8. A surface grinding machine comprising a base, a saddle movably mounted on said base for reciprocating movement relative thereto in one direction, a table movably mounted on said saddle for reciprocating movement relative thereto in a direction transverse to said one direction, a first reversible hydraulic motor operatively coupled to said table, a first hydraulic fluid supply circuit for said first motor, a table reversing valve connected in said first circuit for reversing the direction in which said first motor is driven by the fluid of said first circuit when said table arrives at its extreme positions in its reciprocating movement in said one direction, a second reversible hydraulic motor operatively coupled to said saddle, a second hydraulic fluid supply circuit for said second motor, a saddle reversing valve connected in said second circuit operable to reverse the direction in which said second motor is driven by the fluid of said second circuit, means responsive to the arrival of the saddle in its extreme positions to effect operation of said saddle reversing valve, an increment feed valve means allowing a quantity of fluid to flow into said second circuit when said table is at its extreme positions, and control means for operating said increment feed valve means and said responsive means to provide selective movement of said table and said saddle reciprocating separately and concurrently together, respectively, for step-by-step and criss-cross grinding.

9. A grinding machine according to claim 8, wherein for step-by-step grinding the supply of liquid for said first motor is controlled by direction-reversing valve means which is responsive to the position of said table so that said table is continuously reciprocated, and the supply of liquid for said saddle motor is controlled step-by-step by said increment feed valve means so that said saddle motor is driven step-by-step in said transverse direction.

10. A grinding machine according to claim 9, wherein said increment feed valve means includes a metering valve having two ports, and means for connecting said two ports alternately to a source of hydraulic fluid and for connecting the other of said ports to a port of the saddle motor, said metering valve being such that the connection of each port to said source ejects a metered quantity of the fluid from the other of said ports, whereby metered quantities of the liquid are injected successively through said port of the saddle motor and said saddle motor is driven step-by-step in said transverse direction.

11. A grinding machine according to claim 10, wherein in response to the saddle motor reaching the end of its run in said transverse direction, the step-by-step supply of liquid to said saddle motor is adapted to drive said saddle motor step-by-step in a reverse direction.

12. A grinding machine according to claim 10, wherein said saddle reversing valve means is operable to change the injection of the metered quantities of liquid from the said port of the saddle motor to another port of said saddle motor.

13. A grinding machine according to claim 10, wherein said increment feed valve means further comprises means for controlling the flow of fluid to and from said metering valve, the last said means comprising a reciprocating meter-control valve having one position at which one port of said metering valve is connected to said source and the other of said ports is connected to said port of said saddle

motor and another position at which the other of said ports of said metering valve is connected to said source and said one port is connected to said port of the saddle motor.

14. A grinding machine according to claim 13 further comprising a direction reversing relay controlled hydraulically by said direction reversing valve means, said meter control valve being hydraulically coupled to said direction reversing relay so as to reciprocate in synchronism therewith.

15. A grinding machine according to claim 13, wherein said meter control valve reciprocates in synchronism with the reciprocation of said table.

16. A grinding machine according to claim 9, wherein the step-by-step supply of fluid to the saddle motor is controlled according to the position of the table so as to synchronise with reciprocation of said table.

17. A grinding machine according to claim 12, wherein said saddle-reversing valve means are connected between said meter control valve and said saddle motor.

18. A grinding machine according to claim 8, wherein separate sources of hydraulic supply are provided for said table motor and said saddle motor.

19. A grinding machine according to claim 18, wherein each of said sources includes a pump.

20. A grinding machine according to claim 8, wherein the respective hydraulic motors include cylinders with pistons, said saddle cylinder and said table cylinder are secured to said saddle, said piston of said saddle cylinder being secured to said base, said piston of said table cylinder being secured to said table, and said valve means is secured to said saddle thereby minimising the number of flexible conduits required.

21. A grinding machine according to claim 4, wherein said control means is a unitary control element having a changeover valve for directing a fluid flow from a source selectively to said increment feed valve for step-by-step grinding and to said saddle reversing valve means for criss-cross grinding respectively.

22. A surface grinding machine comprising a base, a saddle mounted on said base, a table movably mounted on said saddle, a first reversible hydraulic means operatively coupled to said table for reciprocating movement of the table along one direction, means automatically reversing the direction of movement of the table at each end of its stroke, a second reversible hydraulic means operatively coupled to said saddle for concurrent and continuous reciprocating movement thereof in a direction transverse to the table, increment feed means automatically moving the saddle a partial distance of its stroke corresponding to step-by-step feed in response to the table arriving at each end of its stroke, reversing means automatically reversing the direction of movement of the saddle at each end of its stroke to provide criss-cross grinding, and control means controlling the period of operation of said increment feed means and said reversing means to provide selectively step-by-step grinding and criss-cross grinding.
